UNITED STATES PATENT OFFICE.

ADOLPH PETZOLD, OF PHILADELPHIA, PENNSYLVANIA, ASSIGNOR TO JOHN H. BROMLEY AND EDWARD BROMLEY, OF SAME PLACE.

DESIGN FOR A RUG.

SPECIFICATION forming part of Design No. 27,002, dated April 27, 1897.

Application filed March 23, 1897. Serial No. 628,917. Term of patent 7 years.

To all whom it may concern:

Be it known that I, ADOLPH PETZOLD, a citizen of the United States, residing in the city of Philadelphia, Pennsylvania, have invented and produced a certain new and original Design for a Rug, of which the following is a full, clear, and exact description, reference being had to the accompanying drawing, forming a part of this specification.

10 My invention relates to the surface ornamentation of a woven rug; and it consists of the design therefor shown in the aforesaid drawing.

15 The distinguishing features of which the design is composed are the narrow rectangular border A and an inner smaller one B, while the space between the two is filled with

a series of leaf and flower figures C, and the field center within the interior border is occupied with a large diamond-shaped figure 20 D, having ends D' and the spaces surrounding the same filled up with ornamental flower figures D².

I claim as new and of my invention—

The design for a rug, substantially as set 25 forth.

In testimony whereof I have hereunto affixed my signature this 26th day of February, A. D. 1897.

ADOLPH PETZOLD.
